CLAIM

The ornamental design for a combined clapper and chime support for wind chimes, as shown and described.

DESCRIPTION

FIG. 1 is an isometric view of a combined clapper and chime support for wind chimes showing my new design;

FIG. 2 is a front elevation view thereof, the back side being a mirror image of that shown;

FIG. 3 is a side elevation view thereof, the opposite side being a mirror image of that shown;

FIG. 4 is a top plan view thereof; and,

FIG. 5 is a bottom plan view thereof.
